ICE EJECTOR TRAY AND BUCKET

Roland J. Bunnell, Durham, N.C., assignor to General Motors Corporation, Detroit, Mich., a corporation of Delaware

Filed Dec. 6, 1965, Ser. No. 511,904

7 Claims. (Cl. 249—69)

This invention relates to a storage bucket or collecting receptacle provided with a camming arrangement cooperating with the movable grid of an inverted tray or mold to eject frozen cubes into the bucket or collecting receptacle.

A number of arrangements such as for example are shown in Patents 2,899,804, issued Aug. 18, 1959 and 2,916,895, issued Dec. 15, 1959, have been devised for ejecting frozen cubes from an inverted tray or mold directly into the storage bucket. Since the use of the patterned metal tray such as is illustrated in Patent 3,033,008, issued May 8, 1962, has permitted the use of much thinner aluminum for these trays or molds to obtain quicker freezing, there is concern whether the trays are strong enough to be used as a lever as illustrated in Patents 2,899,804 and 2,916,895. Although these arrangements are of modest cost, the intensive prior competition has kept them from being made standard in a low priced refrigerator.

It is an object of this invention to provide a very simple effective inexpensive arrangement of an inverted tray or mold and a bucket with a simple means for ejecting the frozen cubes into the bucket which will limit the stress upon the tray or mold.

It is another object of this invention to provide a very simple effective inexpensive camming arrangement effective upon a direct downward movement of the adjacent end of an inverted tray or mold relative to a storage bucket which will move a movable grid within the tray or mold to eject frozen cubes from the tray or mold into the storage bucket.

These and other objects are attained in the forms shown in the drawing in which the tray or mold is provided with a hook shaped bracket or rim portion at one end adapted to hook when inverted upon the adjacent end of an ice bucket or collecting receptacle. The movable grid within the tray or mold has a longitudinally movable actuating bar provided at the opposite end of the tray or mold with a pair of nylon rollers rotatably mounted thereon by a suitable rivet. The rollers engage a cooperating actuating cam surface within the bucket so that when the adjacent end of the tray or bucket is pressed downwardly, the engagement of the rollers with the cam surfaces causes a longitudinal movement of the longitudinal bar to break loose the ice cubes formed within the tray and causes the ice cubes to be released into the bucket. In a second form of the invention the angularity of the cam surface is made manually adjustable and cooperates with a pair of nylon buttons upon the first transverse partition wall of the grid to cause the reaction between the buttons and the cam surface to cause pivoting movement of the first wall and a lateral movement of the longitudinal bar away from the cam surface to free the ice cubes within the grid and causing them to be discharged onto the bottom of the bucket.

Further objects and advantages of the present invention will be apparent from the following description, reference being had to the accompanying drawings wherein preferred embodiments of the present invention are clearly shown.

In the drawings:

FIGURE 1 is a vertical sectional view through an inverted tray or mold upon a bucket disclosing my invention.

2

tion and particularly showing the tray or mold in its starting position;

FIGURE 2 is a fragmentary sectional view similar to FIGURE 1 showing the second position at the completion of the operation of pressing down upon the tray or mold as indicated by the arrow in FIGURE 1; and

FIGURE 3 is a fragmentary sectional view illustrating a modified form of the invention.

Referring now more particularly to FIGURE 1, there is illustrated an ice receiving and ice storage bucket or collecting receptacle 20 of suitable high strength plastic or metal which is rectangular in shape with the ends 22 and 24 being shown in section. According to my invention, an inverted ice tray 26 is inverted over the bucket 20 and has riveted to one end thereof, a U-shaped metal channel 28 which is riveted to the flange 29 of the tray 26. The U-shaped channel 28 when hooked over the end wall 24 as illustrated, effectively limits the longitudinal movement of the tray 26 but permits upward and downward movement of this tray or mold. The tray or mold 26 is preferably of patterned aluminum as illustrated in Patent 3,033,008, issued May 8, 1962, which may be very thin and flexible. The interior of the tray or mold 26 is provided with a longitudinal partition wall 32 having projections 31 and 33 extending through slots in the adjacent ends of the tray or mold 26 and transverse partition walls 34, 36, 38, 40 and 42. These transverse partition walls have vertical slots receiving the longitudinal partition wall 30 as well as the notched longitudinal actuating bar 44. This longitudinal actuating bar 44 moves longitudinally relative to the longitudinal partition wall 32 to pivot the transverse partition walls 34—42 to a vertical position as illustrated in FIGURE 2 to dislodge frozen cubes from the tray 26. The projection 33 is held in place by a transverse spring extending between it and the flange 29. The tray and grid or partition walls and actuating bar may be like those illustrated in Patent 2,874,553, issued Feb. 24, 1959 and are normally held in the position shown in FIGURE 1 by the spring 43 and the bent projection 41 engaged by the wall 30.

According to my invention, for the purpose of providing a simple inexpensive effective arrangement for moving the longitudinal bar to accomplish the release of the frozen cubes 46 from the tray or mold 26, I rivet and rotatably mount to the left end of the notched bar 44, a pair of nylon rollers 48. In the starting position these nylon rollers 48 are located adjacent the end flange 50 of the tray or mold 26. When the tray 26 is inverted with the channel member hooked over the opposite end of the bucket 20, the nylon rollers engage a cam or inclined plane 52 of plastic or metal which is fixed against the bottom and end wall of the bucket 20. The surface of the cam or inclined plane 52 may be at an angle of about 40° to 70° from the horizontal plane. When the tray 26 is pressed downwardly as indicated by the arrow 54 in FIGURE 1 the longitudinal bar 44 is cammed laterally to the right in consequence of the reaction of the downward force of the rollers 48 with the surfaces of the cam 52. The movement of the bar 44 to the right causes the adjacent portions of the transverse partition walls 34—42 to be pivoted substantially to a vertical position relative to the bottom of the tray as illustrated in FIGURE 2. At the beginning of this movement the frozen ice cubes 46 are broken loose from the tray 26 and the partition walls 32 and 42 inclusive, as illustrated in FIGURE 2 and fall by gravity to the bottom of the bucket or receptacle 20. After this, the tray 26 may be turned right side up and filled with water or other liquid to be frozen and placed in the refrigerator for freezing a second batch of ice cubes.

In FIGURE 3 a modified form of the invention is applied to the tray or mold 26. In this form the longitudinal

bar 64 is cut off at the left end. Instead of providing a nylon roller upon the longitudinal bar, there is applied to the first transverse partition wall 66 a pair of large headed nylon rivets 68 which when the tray 26 has the channel 28 hooked over the opposite end of the bucket or receptacle 20 and moved downwardly will be guided to engage the surface of the cam 70 which is pivoted upon the pin 72 to an irregular block 74 fastened by the screws 76 to the adjacent end wall 22 of the bucket 20. The angularity of the cam surface 71 of the cam 70 is adjusted by the set screw 78 which is threaded through the block 74 into engagement with the rear face of the pivoted cam member 70.

Upon their downward movement the engagement of the pair of nylon rivet heads 68 with the cam surface 71 cams the adjacent portion of the transverse wall 66 and the longitudinal bar 64 to the right to dislodge the frozen ice cubes from the spaces between the partition walls and the tray 26. The remainder of tray 26 and the remaining partition walls as well as the remaining portion of the longitudinal bar 64 are preferably like those as shown in FIGURES 1 and 2. It will therefore be observed that I have provided a simple inexpensive camming arrangement for actuating the grid member of an ice tray or mold which limits the amount of force and consequent distortion which can be applied to the tray to effect the disengagement of the cubes.

While the embodiments of the present invention as herein disclosed, constitute preferred forms, it is to be understood that other forms might be adopted.

What is claimed is as follows:

1. A frozen liquid ejecting assembly including a long mold for frozen liquid and a long collecting receptacle for receiving in inverted position said mold, said collecting receptacle and inverted mold having interengaging means adjacent one end for supporting said end of said mold upon said receptacle, the opposite end of said collecting receptacle being constructed to extend outside the path of any downward movement of said mold, said mold being provided with a movable grid, and interengaging cam and cam follower means between said mold and

said receptacle for moving said movable grid to release frozen liquid from said mold for delivery into said receptacle.

2. A frozen liquid ejecting assembly as defined in claim 1 in which the grid has a movable longitudinal bar provided with a cam follower and the receptacle has a cam cooperating with said follower to move said bar.

3. A frozen liquid ejecting assembly as defined in claim 1 in which the movable grid has a transverse partition wall and the cam and cam follower means comprises an element operably connected to said transverse partition wall and an element connected to said receptacle.

4. A frozen liquid ejecting assembly as defined in claim 1 in which the cam and cam follower means comprises a roller follower which rolls upon the surface of the cam.

5. A frozen liquid ejecting assembly as defined in claim 1 in which the movable grid has a movable longitudinal bar and the receptacle is provided with the cam, said bar being provided with a roller follower which rolls upon the surface of the cam.

6. A frozen liquid ejecting assembly as defined in claim 1 in which the cam and cam follower means comprises a means for adjusting the angle of inclination of the cam.

7. A frozen liquid ejecting assembly as defined in claim 1 in which the cam and cam follower means comprises a pivoted cam and an adjusting screw for engaging and holding said cam in various selective angles of inclination.
